UNITED STATES PATENT OFFICE.

FREDERICK L. KEPPLER, OF NEW YORK, N. Y.

CONDENSATION-GUTTER FOR SKYLIGHTS.

1,289,188.

Specification of Letters Patent. Patented Dec. 31, 1918.

Application filed August 3, 1917. Serial No. 184,303.

To all whom it may concern:

Be it known that I, FREDERICK L. KEPPLER, a citizen of the United States, residing at New York, in the county of New York and State of New York, have invented a certain new and useful Improvement in Condensation-Gutters for Skylights, of which the following is a specification.

My invention relates to improvements in condensation gutters for sky-lights and has for one object to provide in connection with a sky-light construction a new and improved form of condensation gutter and drainage system whereby the gutter itself will be insulated from the outside cold thus preventing the formation on the gutter itself. Another object of my invention is to provide a simplified condensation gutter whereby in the minimum obstruction of light will be permitted. Other objects of my invention will appear from time to time in the specification.

My invention is illustrated more or less diagrammatically in the accompanying drawing, wherein—

Figure 1 is a section through a sky light;

Fig. 2 is a part plan view;

Fig. 3 is a section on the line 3—3 of Fig. 2;

Fig. 4 is a section on the line 4—4 of Fig. 3.

Like parts are indicated by like characters in all the figures.

A is a building wall. Mounted upon it is a roof girder A¹. Supported from the wall by any suitable means not here shown is a girder A². A³ are angle or bench plates mounted on the girders A¹ and A². A⁵ is a glass concrete sky light panel or structure supported at its edges on the girder supported plates A⁸, as indicated. This structure forms the roof itself. Its surface is exposed to the atmospheric conditions outside the building, its inner surface to atmospheric conditions inside the building. In cold weather it will be exceedingly cold and the moist air inside coming in contact with the cold inner surface will condense. It is this condensation which my invention provides for carrying away.

The sky light structure is made up as indicated of a series of separate glass tiles B, B which are provided with corrugated upper surfaces B¹ as indicated arranged adjacent one another to contain a concrete or

plastic filling material B² embedded in which is a series of metallic reinforcing bars so that when the concrete has set the tiles are held together as a single unitary translucent structure. Each tile has four downwardly depending sharp edged walls as indicated. Two of them, B³, B³, are parallel with the upper surface of the tile. The other two, B⁴, B⁴, are downwardly and outwardly inclined so that any water of condensation developing on the surface will run down to the walls B⁴ and thence follow the small portion in Fig. 3 to the lowest point of the tile where the water will drip off. The water which thus drips off will be caught in the gutters B⁵, B⁶ which conform to the slope of the roof and discharge into a main gutter B⁷. These gutters B⁵, B⁶ are arranged parallel and owing to the peculiar shape of the lower walls of the glass tile sections no cross gutters are needed, the water being conveyed from each tile to the longitudinal gutters on either side thereof.

These gutters are supported a short distance below the sky light far enough down so that they are insulated by an air cushion from the sky light itself, and thus protected from the extremes of temperature.

The upper ends of the gutters B⁵ are supported on the brackets C resting upon the members A³ and lying beneath the concrete filler which surrounds the outer portion of the sky light. They are thus not directly exposed to the outside atmosphere but insulated by the concrete which forms a considerable insulation and which in view of the small size of the connecting member does not result in any material cooling of the gutter itself. The same arrangement prevails at the lower end where a bracket C¹ supports the gutter resting on the support beneath the sky light structure. This insulating of the concrete is assisted by a thin layer of any suitable insulating material C². This insulating layer may be made of rubber cement, asphalt, fiber board, cork and the like, but rubber cement is particularly suitable for the purpose. This may or may not be used as the case may be depending on the extremes to be encountered and other conditions. C³, C³ are elastic cement expansion joints provided between adjacent sky light sections whereby they may be permitted to expand and contract without danger of springing a leak or the like.

It will be evident that while I have shown in my drawings an operative device, still many changes might be made both in size, shape and arrangement of parts without departing materially from the spirit of my invention and I wish, therefore, that my drawings be regarded as in a sense diagrammatic.

D is a gutter supporting angle iron comprising an angle having one flange extending down across in front of the edge of the member A³, the other flange resting upon that member. The skylight structure itself rests upon such member being insulated from it as at C². The gutter itself is mounted upon the flange being insulated from it at D², the two parts being bolted in position. By this arrangement, of course, the flange supporting the gutter is insulated from the outside and the gutter itself is insulated from the flange so that there is a minimum tendency for any cooling of the gutter itself which would cause it to catch condensation.

25 The use and operation of my invention are as follows:—

With the structure in place, condensation will as indicated form on the under surfaces of the tile. It is a well-known fact that the water of condensation will not let go of the surface until it reaches its lowest point and thus the water will travel along the inclined tile surfaces and be discharged along the lowest straight edge of the tile where it will be caught by gutters beneath the sky light and which being insulated from the outside air are of substantially the same temperature as the room and thus do not give rise to any condensation themselves. 40 This water is carried off by these series of gutters and discharged in any suitable manner. In view of the fact that the tiles are so shaped that all the water discharged is on two opposed sides of the tile, it will be understood that there is no necessity for any cross gutters except at the lower edge to join the inclined lateral gutters together. These inclined gutters being very narrow since the point discharging them is localized by the shape of the tile, will afford a minimum of obstruction to the light coming in through the sky light. The downwardly inclined condensation surfaces as shown lead the water of condensation to the acute drip edges and the water then runs along these acute edges down along the uninclined drip edges where the lowest point is reached and where the water finally drops off into the drip gutters.

60 I claim:

1. A glass tile for sky lights and the like having formed on its under side a plurality of downwardly inclined condensation surfaces terminating in a plurality of connected acute drip edges depending below

the point of support of the tile, some of said edges being inclined downwardly to meet the other edges.

2. A glass tile for skylights and the like consisting of a relatively thin central portion, a thickened tile base portion surrounding it, and a plurality of connected acute drip edges forming the inner side of said base portion.

3. A glass tile for skylights and the like consisting of a relatively thin central portion, a thickened tile base portion surrounding it, and a plurality of connected acute drip edges depending below the point of support of the tile forming the inner side of said base portion.

4. A glass tile for sky lights and the like having formed on its under side a plurality of downwardly inclined condensation surfaces terminating in a plurality of connected acute drip edges, some of said edges being parallel with the top of the tile and others being inclined downwardly to meet them.

5. A sky light structure comprising a supporting framework, a glass tile structure mounted thereon, the undersides of the glass tile being shaped to concentrate the drip of condensation along parallel lines and gutters arranged beneath such lines adapted to catch the condensation said gutters being out of contact with the tiles and the members directly supporting them.

6. A sky light structure comprising a supporting framework, a glass tile structure mounted thereon, the underside of the glass tile being shaped to concentrate the drip of condensation along parallel lines and gutters arranged beneath such lines for condensation adapted to catch the condensation said gutters being out of contact with the tiles and in contact with the supporting framework only at the edges of the tile structure.

7. In a sky light structure the combination of a tile supporting framework, approximately rectangular tiles supported thereon the lower surfaces of which terminate on two opposite sides in acute condensation drip edges, said tiles being arranged to form parallel lines of drip edges, with parallel gutters arranged beneath such parallel drip edges said gutters being out of contact with the tiles and the members directly supporting them.

8. In a tile skylight structure, the combination of tiles whose lower edges form parallel drip edges, with a plurality of parallel gutters arranged beneath the drip edges, said gutters being out of contact with the tiles and the members directly supporting them.

9. In a tile skylight structure, the combination of tiles whose lower edges form parallel drip edges, with a plurality of par-

allel gutters arranged beneath the drip edges, said gutters out of contact with the tile and the members directly supporting them, said gutters supported only at their 5 ends.

10. In a tile skylight structure, the combination of tiles whose lower edges form parallel drip edges, with a plurality of parallel gutters arranged beneath the drip edges, said gutters out of contact with the 10 tile and the members directly supporting

them, said gutters supported only at their ends, and being insulated at their ends from the tile supporting structure.

In testimony whereof, I affix my signature in the presence of two witnesses this 18th day of July, 1917.

FREDERICK L. KEPPLER.
